UNITED STATES PATENT OFFICE.

HENRY BERGER, OF NEW YORK, N. Y.

DESIGN FOR CENTER-PIECE.

Specification forming part of Design No. **11,328**, dated August 12, 1879; application filed July 2, 1879.
[Term of patent 7 years.]

To all whom it may concern:

Be it known that I, HENRY BERGER, of the city, county, and State of New York, have invented a new Design for Center-Piece, of which the following is a full, clear, and exact description, reference being had to the accompanying photograph, which represents a face view of my design.

My design consists in a central shield formed of a rosette, a series of leaves, and a circular band, in combination with a series of cuneiform projections surrounding said shield and alternately terminating in ornamental escutcheons and in arabesques, which are arranged on a circular panel, whereby I obtain a design presenting a handsome and distinguishing appearance.

In the drawing, the letter A designates a rosette, B are a series of leaves, and C is a circular band, composing the central figure or shield of my design, the leaves B being arranged in a circle around the rosette and the band C being made to surround the leaves. Next the circular band C are a series of cunei-

form projections, D, which alternately terminate in ornamental escutcheons E and arabesques F, while these escutcheons and arabesques rest on the surface of a panel, G, having a circular form, and project slightly beyond the edge of said panel.

What I claim as new, and desire to secure by Letters Patent, is—

The design for a center piece consisting of a central shield formed of a rosette, A, a series of leaves, B, and a circular band, C, in combination with a series of cuneiform projections, D, surrounding said central shield, and alternately terminating in ornamental escutcheons E and in arabesques F, which are arranged on a circular panel, substantially as shown and described.

In testimony that I claim the foregoing I have hereunto set my hand and seal this 16th day of July, 1877.

HENRY BERGER. [L. S.]
